(57) **CLAIM**

The ornamental design for a sign face, as shown and described.

DESCRIPTION

FIG. 1 is a perspective view of a first embodiment of the sign face of our new design.

FIG. 2 is a front view of the first embodiment of the sign face of our new design.

FIG. 3 is a right side view of the first embodiment of the sign face of our new design. The left side view is a mirror image of FIG. 3.

FIG. 4 is a rear view of the first embodiment of the sign face of our new design.

FIG. 5 is a top view of the first embodiment of the sign face of our new design. The bottom view is a mirror image of FIG. 5.

FIG. 6 is a perspective view of the second embodiment of the sign face of our new design.

FIG. 7 is a front view of the second embodiment of the sign face of our new design.

FIG. 8 is a right side view of the second embodiment of the sign face of our new design. The left side view is a mirror image of FIG. 8.

FIG. 9 is a rear view of the second embodiment of the sign face of our new design; and,

FIG. 10 is a top view of the second embodiment of the sign face of our new design. The bottom view is a mirror image of FIG. 10.
